US0D1037661S

(12) United States Design Patent (10) Patent No.: US D1,037,661 S
(45) Date of Patent: * Aug. 6, 2024

(54) MANICURE CASE

(71) Applicant: Shenzhen Zhuifei Trading Co., Ltd.,
Shenzhen (CN)

(72) Inventor: Hui Dong, Shenzhen (CN)

(73) Assignee: Shenzhen Zhuifei Trading Co., Ltd.,
Shenzhen (CN)

() Term: 15 Years

(21) Appl. No.: 29/924,207

(22) Filed: Jan. 18, 2024

(51) LOC (14) Cl. 03-01

(52) U.S. Cl.

USPC D3/274; D3/279; D3/295; D6/642

(58) Field of Classification Search

(57) CLAIM

The ornamental design for a manicure case, as shown and described.

DESCRIPTION

FIG. 1 is a front perspective view of a manicure case, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof, showing the top two latch features in an unclasped configuration;

FIG. 7 is a top view thereof;

FIG. 8 is a bottom view thereof;

FIG. 9 is a perspective view of the manicure case of FIG. 1, showing the manicure case in an opened configuration with the detachable table feature in an extended state;

FIG. 10 is a perspective view of the manicure case of FIG. 1, showing the manicure case in a partially opened configuration with the detachable table feature in an extended state; and,

FIG. 11 is a perspective view of the manicure case of FIG. 1, showing the manicure case in a closed configuration with the detachable table feature in an extended state.

1 Claim, 11 Drawing Sheets
